DESIGN FOR A SEPARATING CONTAINER

Norman P. Miller, West Los Angeles, Calif.

Application January 8, 1944, Serial No. 112,265

Term of patent 14 years

(Cl. D58—12)

To all whom it may concern:

Be it known that I, Norman P. Miller, a citizen of the United States of America, residing at West Los Angeles, in the county of Los Angeles, State of California, have invented a new, original, and ornamental Design for a Separating Container, of which the following is a specification, reference being had to the accompanying drawing, forming a part thereof.

Fig. 1 is a top front perspective view of a separating container showing my new design illustrated with the slidable cover positioned substantially midway between the ends of the container,

Fig. 2 is a top front perspective of the container, taken at a slightly different angle, with the slidable cover in its right-hand position,

Fig. 3 is a perspective view similar to that of Fig. 2 but with the cover in its left-hand position, and

Fig. 4 is a sectional view of the container with the cover in a position corresponding to that of Fig. 3.

I claim:

The ornamental design for a separating container, as shown and described.

NORMAN P. MILLER.
